CAN PERFORATOR

Rudolph C. Kulling, Chicago, Ill.

Application December 12, 1938, Serial No. 245,258

1 Claim. (Cl. 220—51)

The present invention relates to new and useful improvements in openers or perforators for metallic containers, particularly evaporated or condensed milk cans and has for its primary object to provide, in a manner as hereinafter set forth, a device of this character embodying a construction and arrangement whereby pouring and vent openings may be simultaneously formed in the top of a can with a minimum of effort.

Another very important object of the invention is to provide a can perforator of the aforementioned character comprising novel means for assisting in withdrawing the punches from the can top after the perforations have been made therein.

Still another very important object of the invention is to provide a can perforator of the character described embodying a novel striking surface whereby driving the punches through the can top will be materially facilitated.

Other objects of the invention are to provide a can perforator of the character set forth which will be comparatively simple in construction, strong, durable, highly efficient and reliable in use, compact and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

35 Figure 1 is a vertical sectional view through a can perforator constructed in accordance with the present invention, showing same in position on a milk can.

Figure 2 is a bottom plan view of the device.

40 Figure 3 is a perspective view, showing the device mounted on a milk can.

Figure 4 is a detail view in bottom perspective of the metallic cover which provides the pushing or striking surface.

45 Figure 5 is a detail view in perspective of one of the punches.

Figure 6 is a perspective view of the upper portion of a milk can, showing two openings which have been made therein.

50 Figure 7 is a perspective view of the cup.

Figure 8 is a fragmentary view in vertical section, illustrating the position of the device on a can when the punches have perforated the top of said can.

55 Referring now to the drawings in detail, it will

be seen that the embodiment of the invention which has been illustrated comprises a cup of any suitable metal which is designated generally by the reference numeral 1. The cup includes a circular top 2 and a depending annular skirt 3. 5 As will be readily apparent, the cup 1 is adapted to be slipped on the top portion of a conventional milk can 4. Of course, the cup 1 may be of different diameters to accommodate different sizes of cans.

10 Mounted in the cup 1 adjacent diametrically opposite sides thereof is a pair of punches 5. The punches 5 include reduced threaded shanks 6 which extend through openings 7 which are provided therefor in the top 2 of the cup 1. Nuts 15 8 are threaded on the shanks 6 for securing the punches 5 in position. The reduced shanks 6 provide shoulders 9 on the punches 5 which are engageable beneath the top 2 of the cup 1.

15 Also, the shanks 6 include flat side portions 10 20 which are engageable with corresponding portions of the walls of the openings 7 for positively preventing rotation of said punches in said openings. The lower ends of the punches 5 are bevelled in a manner to provide penetrating points 11.

25 The reference numeral 12 designates generally a substantially V-shaped lifting spring of suitable resilient metal which is mounted in the cup 1 for engagement with the top 13 of the can 4. The spring 12 includes a narrow flat intermediate portion 14 which is perforated to accommodate fastening elements 15 which firmly secure said spring in position beneath the top 2 of the cup 1.

30 The spring 12 further includes oppositely inclined arms 16 which extend from the intermediate portion 14. As illustrated to advantage in Fig. 2 of the drawings, the side edges of the arm portions 16 of the spring 12 converge toward the intermediate portion 14 thereof. The free ends of the arms 16 of the spring 12 are 35 notched or recessed, as at 17, to avoid contact with the punches 5. Also, the arms 16 terminate in outturned lips 18 on their free ends which are adapted to slidably engage the top of the can to be opened. The top 2 of the cup 1 has formed 40 therein openings 19 which accommodate the securing elements 15.

45 Mounted on the top 2 of the cup 1 is a cover for the elements 6, 8, 15, etc., which is designated generally by the reference numeral 20, said cover 50 also being of any suitable metal. The cover 20 is substantially oval in plan and said cover includes a top 21 and a depending flange 22. Formed integrally with the lower edge of the flange 22 is a plurality of tongues 23 which are engageable in 55

openings 24 which are provided therefor in the top 2 of the cup 1. The tongues 23 are clinched beneath the cup top 2 for rigidly securing the cover 20 in position.

5 It is thought that the manner in which the device is used will be readily apparent from a consideration of the foregoing. The cup 1 is slipped on the top of the can 4 and the device is normally supported in elevated position on the can by the 10 spring 12. Now, by pushing downwardly or striking the flat, smooth top 21 of the cover 20 the device is driven downwardly on the can against the tension of the spring 12 in a manner to cause the punches 5 to perforate the top 13 15 of said can. This is shown to advantage in Fig. 8 of the drawings. After the can has been thus perforated the device is returned to elevated position by the spring 12, thus withdrawing the punches 5 from the openings which have been 20 made. The device may then be removed or, if desired, it may be left on the perforated can to function as a cover therefor. During the punching operation the skirt 3 of the cup 1 acts as a 25 guide for the punches 5. It will thus be seen that two openings are formed simultaneously in the can top closely adjacent diametrically opposite sides thereof. In Fig. 6 of the drawings, these

openings are designated by the reference numeral 25. The milk is poured through one of these openings and the other functions as a vent.

It is believed that the many advantages of a can perforator constructed in accordance with the present invention will be readily understood and although a preferred embodiment of the device is as illustrated and described, it is to be understood that changes in the details of construction and in the combination and arrangement of parts may 10 be resorted to which will fall within the scope of the invention as claimed.

What is claimed is:

A can perforator comprising a cup adapted to be mounted on a can, punches mounted in the 15 cup and including shanks extending through the top thereof, said punches being adapted to perforate the can, nuts threaded on the shanks for securing the punches in position, and a cover for enclosing the shanks and the nuts mounted on 20 the top of the cup, said cover including a substantially smooth, flat top constituting a striking surface for driving the punches through the can, said cover further including a depending marginal flange secured to the cup. 25

RUDOLPH C. KULLING.
